(57) CLAIM

The ornamental design for a hair packaging, as shown and described.

DESCRIPTION

FIG. 1 is a perspective view of a hair packaging showing my new design;

FIG. 2 is a perspective view thereof with an internal tray removed therefrom;

FIG. 3 is a front view of the hair packaging shown in FIG. 1;

FIG. 4 is a left side view thereof;

FIG. 5 is a right side view thereof;

FIG. 6 is a back view thereof;

FIG. 7 is a top view thereof; and,

FIG. 8 is a bottom view thereof.

The broken lines shown in the drawings depict portions of the hair packaging that form no part of the claimed design.

1 Claim, 3 Drawing Sheets
